UNITED STATES PATENT OFFICE

92,626

DESIGN FOR AN ASH TRAY

Forrest G. Purinton, Waterbury, Conn., assignor
to The Patent Button Company, Waterbury,
Conn., a corporation of Connecticut

Application November 3, 1933, Serial No. 49,642

Term of patent 14 years

To all whom it may concern:

Be it known that I, FORREST G. PURINTON, a citizen of the United States, residing at Waterbury, in the county of New Haven and State of Connecticut, have invented a new, original, and ornamental Design for Ash Trays, of which the following is a specification, reference being had to the accompanying drawing forming part thereof, in which:

Fig. 1 is a plan view of an ash tray, showing my new design;

Fig. 2 is a side elevation thereof;

Fig. 3 is an enlarged sectional view of the same, on a slightly enlarged scale for the purpose of clearness of illustration.

The cross-hatching in the several views indicates color, although applicant does not wish to be limited to any specific color.

I claim:

The ornamental design for an ash tray, as shown and described.

FORREST G. PURINTON.
